FOOT SHIELD BODY

Jeremiah J. Boughey, Chicago, Ill., assignor of one-third to J. Roy Abell, Evanston, Ill., and one-third to George E. Semple, Park Ridge, Ill.

Application August 21, 1948, Serial No. 148,231

Term of patent 14 years

(Cl. D7—7)

To all whom it may concern:

Be it known that I, Jeremiah J. Boughey, a citizen of the United States and a resident of Chicago, county of Cook, and State of Illinois, have invented a new, original, and ornamental Design for a Foot Shield Body, of which the following is a specification, reference being had to the accompanying drawing, forming a part thereof, in which Fig. 1 is a perspective view of a foot shield body showing my design; Fig. 2 is a side view of the same on a scale less than that of Fig. 1; Fig. 3 is a top view thereof on the scale of Fig. 2; and Fig. 4 is a transverse vertical sectional view through a part of the body as taken on the line 4—4 of Fig. 2.

The broken lines showing in Fig. 1 are for illustrative purposes only.

I claim:

The ornamental design for a foot shield body, substantially as shown and described.

JEREMIAH J. BOUGHEY.
